York, N. Y., a corporation of New York

Application September 22, 1933, Serial No. 690,560

11 Claims. (Cl. 48—52)

This invention relates to acetylene generators of the carbide to water type.

The invention relates more particularly to that class of generators of the carbide to water type, in which a feed valve at the mouth of the carbide hopper is agitated by a means actuated by outflow of gas from the generator, to feed the carbide. The term valve is used in a general sense, since the feed valve may be said to include an element herein termed a feed plate and the mouth or spout of the hopper with which the feed plate cooperates. Either of these parts of the feed valve may be agitated to effect feeding of the carbide. In the generators illustrated in my Patents No. 1,969,121, dated August 7, 1934, and Nos. 1,967,293 and 1,967,294, dated July 24, 1934, the feed plate is agitated, while in my Patent No. 1,970,225, dated August 14, 1934, it is the spout that is agitated.

20 The invention further relates to generators in which the size of the feed passage between the feed plate and the hopper mouth is regulated, by and in accordance with generator pressure, by raising and lowering of the feed plate, and in 25 which the conformation of the valve is such, and the limit to which it can be moved away from the hopper mouth is such, that the feeding of carbide can not occur in the absence of agitation.

Regular feeding of the carbide is important in 30 order to insure continued generation of gas and to obtain a high quality of pressure regulation for the generator. Choking of the feed is sometimes caused by bridging of the carbide. Bridging may occur at two different points; one of these is just 35 over the spout or mouth at the bottom of the hopper, and the other is between the feeding plate and the hopper mouth.

The use of a flat feed plate results in very 40 irregular feeding. While the displacement of a flat plate is increasing with slowly decreasing generator pressure, the carbide is frequently bridged across the valve opening in such a manner that little or no carbide is discharged. With 45 increasing displacement there comes a time when the bridge breaks and permits the carbide, in considerable quantity, to be discharged into the water. The result is very poor pressure regulation for the generator.

If a conical feed plate is used, there is less 50 likelihood of bridging because a smooth conical surface forms a better sliding surface for the discharging carbide than does a small mass of relatively stationary carbide in the center of a flat plate, and the movements of the cone are 55 instrumental in preventing bridging of the car-

bide across the mouth of the hopper. A conical plate, however, is liable to cause free feeding, unless the distance through which the plate can be displaced away from the hopper mouth is rather limited.

By "free feeding" is meant a continuous run of carbide from the hopper when the valve is open and not agitated. Where free feeding is rapid enough, it is quite possible for a hazardous condition to develop, even though the generator 10 contains the normal amount of water, particularly if it is possible for the carbide feeding plate to be blocked in wide open position. A much more dangerous condition is produced by free feeding of a considerable amount of carbide into 15 the bottom of a generator from which the water has been drained. If then water is admitted to the generator, dangerous heating is likely to take place, for when water is poured into a considerable mass of carbide a temperature of 400° F. may 20 readily be reached. The presence of air in the generator at the time may result in a severe explosion.

With the flat type of plate, if the maximum possible valve displacement is limited sufficiently 25 to prevent free feeding, bridging will frequently become so serious as totally to obstruct the further discharge of carbide. Because of the greater tendency of a conical plate toward free feeding, the valve displacement must be rather narrowly 30 restricted when a conical plate is used, with the result that this type of plate also tends to obstruct the discharge at times.

It is an object of this invention to provide improved apparatus for controlling the feeding of 35 carbide from the hopper of an acetylene generator so as to obtain a regular feed uninterrupted by choking and not subject to free feeding.

Another object of the invention is to make it 40 possible to provide for relatively large valve displacements without danger of free feeding.

Another object of the invention is to improve the reliability of agitation and feeding at low 45 gas flows from the generator. In accordance with this part of the invention, which is not necessarily limited to the preferred form of the feed plate, the feed plate is agitated vertically.

Another object of the invention is to simplify 50 the mechanism. In accordance with this part 50 of the invention, the agitation is transmitted to the feed plate through the regulating lever which regulates the displacement of the plate. This embodiment of the invention involves a special provision for insuring adequate rates of agitation 55

and feeding under all conditions of flow, including large gas flows.

In another embodiment of the invention agitation of the carbide is effected by oscillating the feed plate about a vertical axis. In either case, the agitation of the valve or valve plate is dependent on the rate of flow of gas from the generator and is produced by a gas-operated motor or agitation device of suitable character, forms of which are illustrated in my aforesaid patents.

Other objects, features and advantages of the invention will appear or be pointed out as the description proceeds.

In the accompanying drawings, forming part hereof:

Fig. 1 is a fragmentary vertical section through the upper part of an acetylene generator embodying the invention;

Fig. 2 is a horizontal section on the line 2—2 of Fig. 1;

Fig. 3 is a fragmentary view, mostly in vertical section, showing a modified form of the invention;

Fig. 4 is a sectional view on the line 4—4 of Fig. 3; and

Fig. 5 is a fragmentary vertical section illustrating a modified form of the carbide feed valve.

The upper portion of the generator tank body 30 2 is of truncated conical shape and supports a carbide hopper 3. During the ordinary operation of the generator the tank body is filled with water 4 to the level indicated, and the space 5 is filled with gas.

35 A flange 6 is secured to the top edge of the tank body. The hopper 3 is detachably fastened to this flange by bolts 7 which pass through a flange 8 of the carbide hopper. A sloping bottom 9 of the hopper has a broad feed opening 10 beneath which is a feed plate 11.

40 The feed plate or valve plate 11 moves vertically to change the size of the opening between this plate and the lip of the spout at the feed opening 10. In Figs. 1 and 2 the feed plate is agitated vertically, and this agitation causes the carbide to feed through the opening and drop into the water 4.

45 The feed or valve plate 11 has a conical central portion 12 adapted to extend more or less into the opening 10. The valve plate has a peripheral portion 13 which is flat, as shown in Fig. 1, or slightly inclined as shown in Fig. 3. The change in slope between the portions 12 and 13 of the valve plate may be either abrupt or gradual. The base of the conical portion is preferably 50 smaller than the feed opening 10, and the relatively flat portion extends outward beneath the lip of the opening.

55 Nothing is accomplished by making the base of the conical portion larger than the inner diameter of the hopper spout. It is comparatively ineffectual if less than one-half of the spout diameter, and it should preferably be about two-thirds or three-fourths of that diameter. While the above relationship should be approximated, the included angle at the apex of the cone should 60 preferably be on the order of 140°, representing a slope of about 20°. A peripheral portion having a slope of about 5° has been found to give the best results, but a flat peripheral portion, such as shown in Fig. 1, representing a slope of zero degrees may be used.

70 While a feed plate having a conical portion surrounded by a comparatively flat portion is preferred, the beneficial effects obtained with

such a plate may be approximated by using a feed plate 211, the top of which is a concave surface of revolution of a curve, as shown in Fig. 5.

With the feed plate of this invention, reasonably large valve displacements are possible without free feeding, and the movements of the conical portion agitate the carbide in the hopper mouth in such a manner as to lessen the tendency to choke or bridge at that region. The 10 relatively flat peripheral portion 13 breaks the momentum of the carbide passing from the conical portion 12 and requires the combination of the weight of the carbide above and an agitation of the carbide adjacent the feed plate to effect 15 feeding of the carbide.

15 The valve plate 11 is loosely supported on an enlarged rounded head 17 of a valve stem 14 which extends into a recess in the bottom side of the valve plate. This valve stem is slideable vertically in the hub of a spider 15 which is supported by a collar 16 secured to, and extending down from, the hopper bottom 9.

20 A wide splash ring 19 is secured to the top of the body and extends downward close to the water to prevent water from splashing on the valve plate and its operating mechanism when the generator is being moved.

25 An internally threaded connection collar 20 is welded in an opening in the wall of the tank 30 body 2, and a nipple 21 extends from the collar 20 through an opening in the splash ring 19. A hollow casting 22 has one end threaded into the collar 20. This construction constitutes a latterly extending gas limb communicating with 35 the gas space of the generator.

30 An opening in the top of the gas limb is covered by a diaphragm 26, which is clamped between a bonnet 27 and a seat around the opening in the gas limb. A regulating spring 28 bears against a diaphragm plate 29. The pressure of this spring can be adjusted, to vary the working pressure of the generator, by an adjusting screw 30 threaded through the top of the bonnet and acting on a follower 31 which 45 bears against the upper end of the spring.

35 A relief valve bonnet 32 is preferably integral with the bonnet 27, and covers a relief valve which includes a diaphragm 33 pressed against the lip of an opening in the gas limb by a spring 34 acting against a diaphragm plate. A stem 35 extends from the diaphragm plate through the top of the bonnet 32 and can be raised to open the relief valve manually at any time. Gas 50 escapes from within the bonnet 32 through a 55 vent, not shown.

40 The under side of the diaphragm 26 bears against a spring 38 carried by a cup 39 on a regulating lever 40. For convenience this spring will be termed the reserve spring. The inner end of this lever supports the valve stem 14, and small movements of this lever controlled by the pressure-responsive regulator device, which includes the diaphragm 26 and spring 28, move the valve plate 11 toward or from the hopper mouth and 55 control the amount of carbide fed for a given rate of agitation. The regulating spring 28 acts on the lever 40 through the reserve spring 38, which serves as an elastic thrust connection.

45 The lever 40 is fulcrumed at its outer end on 70 ball fulcrums 45 held in internal lugs 46 of the gas limb so that these fulcrums are fixed with respect to the body of the generator. This end of the lever is preferably bifurcated. The actual lifting or closing of the feed plate 11 is effected 75

by a compensating spring 47 compressed between the gas limb and the bottom side of the lever 40. The regulating spring 28 is stronger than the spring 47, and whenever the pressure in the generator drops slightly the regulating spring 28 overcomes the spring 47 to a corresponding extent and moves the lever down, causing the feed plate 11 to descend so that the feed passage is somewhat enlarged. When the gas pressure rises it acts on the diaphragm 26 to press the regulating spring 28 back slightly so that the spring 47 lifts the valve plate 11 and decreases or even completely closes the feed passage.

The strengths of the reserve spring 38 and the compensating spring 47 are so proportioned with respect to the length of the lever arms against which the springs are compressed that the springs exert substantially balanced forces on the lever 40.

20 The generator can be locked against feeding by holding the valve plate 11 closed against the lip of the mouth of the hopper. This is effected by the spring 47 when the regulating spring 28 is drawn back by raising a stirrup bar 49 by means of a handle 50. The stirrup bar 49 passes through a slot 51 in a boss 52 secured to the diaphragm plate 29; this slot being high enough to permit the diaphragm to rise and fall without being hindered by the bar. Two vertical stirrup rods 53 are connected at their lower ends with the bar, and extend upward through openings in the follower 31 and in the top of the bonnet 27. Their upper ends are connected to a yoke 54, which rests on a cam 55, from which the handle 50 projects. The cam has inclined under surfaces 57 to coat with inclined surfaces on the top of the bonnet, so that by a partial turn of the handle the diaphragm plate and the lower end of the regulating spring 28 can be drawn upward sufficiently to permit the compensating spring 47 to close the plate 11 against the mouth of the hopper and keep the valve tightly closed when the generator is not in use.

In this embodiment of the invention, an adjustable bushing 58 is screwed into the yoke 54 and bears on the cam 55. By means of this device, the opening of the carbide feed valve (displacement of the feed plate) can be adjusted to that maximum degree which will not permit free feeding. When, with falling generator pressure, the regulating spring 28 has depressed the diaphragm plate 29 and the diaphragm 26 until the top of the slot 51 of the boss 52 bears against the stirrup bar 49 as an abutment means, the pressure of the regulating spring 28 is sustained rigidly by the stirrup, and the force of the spring 28 is no longer applied to the control lever 40. The reserve spring 38 then reacts against the diaphragm and diaphragm plate as if against a fixed abutment, and the position of the lever 40 and of the valve plate 11, which is supported by the lever is determined by the balance of moments, the reserve spring 38 and the compensating spring bearing against the lever in opposition to each other. If the springs 38 and 47 are very accurately made so that, at this equilibrium, the feed plate is supported at a maximum displacement which will not admit of free feeding, the adjusting device 58 could be omitted. Its utility is to enable the full open position, which the feed plate can assume and still not result in free feeding, to be predetermined for each generator notwithstanding the variations of ordinary manufacturing tolerances. Naturally, means may be provided for locking this adjustment.

The carbide feed plate 11 is agitated to cause the carbide to feed from the hopper at a rate which is partly dependent on the displacement of the feed plate and partly on the rate of agitation, this latter being in turn dependent on the rate of flow of gas from the generator. The feed plate 11 is agitated by a gas motor device 59 which includes a pot 63 fixed to the under side of the gas limb under an opening. The pot is partially filled with liquid through a filling opening, which is ordinarily closed by a plug 65. This opening is located at the desirable liquid level and prevents the pot 63 from being filled too full.

A flexible diaphragm 66 is clamped at its margin between the gas limb and the pot 63. This diaphragm is thus exposed on its upper side to the pressure in the generator, and on its under side to the pressure of the gas above the liquid in the pot 63. A gas outlet passage 67 communicates with this gas space beneath the diaphragm and conducts the gas to an outlet pipe 68 leading to the usual flash arrester (not shown) from which the gas flows to the service line. A splash ring 86 on the inside of the pot 63, above the liquid, catches liquid which would otherwise be entrained by the rising gas and carried out through the gas outlet, necessitating frequent replenishment of the sealing liquid.

A duct 69 communicates with the gas limb above the diaphragm 66 and extends below the diaphragm to a point near the bottom of the pot 63. When there is no gas pressure in the generator, the liquid in this duct 69 stands at the same height as the liquid in the pot. During generation and consumption of gas, the pressure of the gas in the generator depresses the liquid in the duct 69 until the gas escapes from the lower end of the duct and bubbles up through the liquid in the pot 63 and passes to the outlet 67. With each such escape of gas into the pot 63 the pressure above the liquid in the pot increases and causes the liquid in the duct 69 to rise. As gas flows through the outlet 67, the pressure above the liquid in the pot again decreases until there is a fresh escape of gas from the duct 69.

These discharges of gas through the liquid seal occur at short intervals, the frequency depending upon the consumption flow. The fluctuations in the pressure differential across the diaphragm 66 cause it to flex up and down, and this movement is communicated to the feed plate 11.

The diaphragm 66 is connected with a link 70. The upper end of this link is connected with a lever 72 which has a fulcrum 74 on the gas limb and bears against a boss 75 on the lever 40. The fulcrum 74 comprises a pin connection between the lever 72 and gas limb affording the lever a small amount of movement in a vertical plane.

Flexing of the diaphragm 66 causes the link 70 to oscillate the lever 72 vertically, and this movement of the lever 72 is transmitted through the boss 75 to the lever 40, which in turn transmits the movement through the stem 14 to the feed plate 11 to agitate the feed plate vertically.

It will be observed that the small agitation movement which is transmitted to the regulating lever 40, and by that lever transmitted to the valve plate 11, is permitted by the elasticity of the springs 38 and 47. Because of the presence of the reserve spring 38, the agitating action is not damped or hampered by the necessity of overcoming the stiffness of the regulating spring 28, which must be strong enough to cope with the gas pressure on the diaphragm 26. This is particularly important when the consumption of

gas from the generator is heavy, and the large outflow of gas calls for very active agitation of the feed plate. At very low flows, the vertically agitated feed plate has an inherent advantage over other types of agitation, in that the mild or infrequent agitation which takes place under such conditions is nevertheless sufficient, with vertical agitation, to insure that feeding of carbide will not entirely cease.

10 The agitation of the lever 72 may be caused by other types of gas motor devices than that described. Other suitable gas motor devices are disclosed in my Patents Nos. 1,969,121, 1,967,293 and 1,967,294.

15 Figs. 3 and 4 show mechanism for oscillating a valve plate 111, of the novel form described in the earlier part of this specification, about a vertical axis as in my aforesaid patents.

20 The valve-oscillating mechanism shown in Fig. 3 is similar to that in Patent No. 1,967,293, and includes a bell-crank 170 having a pivot fulcrum 171 supported by a lever 140. One arm of the bell-crank is connected to the link 170 and the other arm connects with a link 175 which extends 25 through the gas limb and terminates in an upwardly extending end portion 180. This end of the link 175 is supported from the lever 140 by a pin 182.

25 A link 184 is eccentrically connected to the 30 valve plate 111 by a pivot connection 186. The end of the link 184 remote from the valve plate is formed in a loop and fits over the upwardly extending end of the link 175. A collar 188 on the link 175 supports the looped end of the 35 link 184.

30 The lever 140 is moved to open and close, and to regulate the displacement of, the valve 111 by mechanism similar to that already described, and differs from the mechanism shown in Fig. 1 in 40 that the reserve spring 38 and cup 39 are omitted and a projection 190 on the under side of the diaphragm 26 bears directly against a boss on the lever 140. Also, the adjusting device 58 is omitted. In this instance, the maximum opening of 45 the valve 111 is limited by the enlarged head of the valve stem 14 abutting against the hub of the spider 15 and preventing further downward movement of the valve feed plate 111 before it has opened wide enough to permit free feeding.

50 As in my prior patents, the supporting of the feed plate on the head of a separate valve stem 14, which enters a cavity in the bottom of the feed plate, enables the feed plate to tilt universally in response to the action of the carbide being fed and thus adjust itself to feeding conditions, with results that are beneficial. The rounded head 17 in the cavity of the plate is 55 more desirable than the point contact shown in my prior patents. In the case of a feed plate which is agitated by oscillating it about the vertical axis, the rounded head affords an element of friction which makes for steadier action.

60 Various changes and modifications may be made in the form of execution of the features of the invention.

65 I claim:

1. An acetylene generator including a carbide hopper, a feed plate at the mouth of the hopper, a lever operatively connected with the feed plate for regulating the displacement of said feed plate, a fulcrum for said lever, pressure-operated means connected with the lever at a substantial distance from said fulcrum for moving the lever to control the feed plate displacement, and other means operatively connected with the lever at a substantial distance from the fulcrum and from

the connection of the lever with the feed plate for agitating said lever to agitate the feed plate.

2. In an acetylene generator having a body, a carbide hopper, a valve movable toward and from the hopper mouth to control the rate of feed of carbide from the hopper, pressure operated means fixed to the generator for controlling the extent of opening of the valve, other means for agitating the valve, a common lever connecting the controlling means and the agitating means with the feed valve, said lever extending transversely of the direction of movement of the valve toward and from the hopper mouth, and a fulcrum for said lever fixed with respect to the body of the generator.

15 3. In an acetylene generator, the combination with a carbide hopper having a feed opening; of a feed plate beneath said opening; a lever supporting said feed plate; a compensating spring acting upon said lever to raise the feed plate 20 when the gas pressure increases; a device including a regulating spring effective to move said lever in opposition to said compensating spring when the gas pressure decreases; a reserve spring interposed between said gas-pressure responsive 25 device and said lever; a gas-operated agitator; and mechanism for applying the agitation of said agitator to said lever, to agitate said feed plate.

4. In an acetylene generator, the combination 30 with a carbide hopper having a feed opening; of a feed plate beneath said opening and movable toward and from the opening to control the discharge of carbide from the hopper; a regulating lever extending transversely of the direction of 35 movement of the feed plate and operatively connected with the feed plate; a fulcrum for said lever; and means for rocking the regulating lever about its fulcrum to raise and lower said feed plate, including gas-pressure responsive means to 40 regulate the displacement of the feed plate; a gas-operated agitator; and means for transmitting vibration from the agitator to the feed plate through the regulating lever including a lever connected to said agitator and having contact 45 with said regulating lever.

5. In an acetylene generator, a carbide hopper; a feed plate beneath the mouth of the hopper; a substantially vertical valve stem having a rounded head supporting the feed plate for 50 tilting movement in all directions about a horizontal axis and oscillation about the axis of the valve stem; means for agitating the feed plate; and mechanism for moving the valve stem to regulate the displacement of the feed plate from 55 the hopper mouth.

6. An acetylene generator including in combination, a carbide hopper having a feed opening; a vertically agitated feed plate for controlling the feeding of carbide from the hopper; a regulating lever operably connected with the feed plate, feed plate operating means for moving said lever to raise and lower the feed plate to control its displacement from the hopper opening, and other means operably connected with the lever for transmitting agitations through the lever to the feed plate, and a fulcrum for said lever spaced from its connections with the raising and lowering means and the agitating means.

7. An acetylene generator including in combination, a carbide hopper having a feed opening; a vertically agitated feed plate beneath said opening; gas pressure operated mechanism for controlling the displacement of the feed plate; an agitating device; a common lever for trans- 75

mitting motion of said mechanism, and agitation of said agitating device, to the feed plate; and a fulcrum for the lever; said mechanism and said agitating device being connected with the lever at a distance from the fulcrum.

- 5 8. In an acetylene generator, a carbide hopper; a feed plate located beneath the mouth of the hopper and having a central conical portion for preventing arching in the hopper mouth, and a peripheral portion of less slope adapted to prevent free feeding of the carbide, a substantially vertical valve stem having a rounded head supporting the feed plate for tilting movement in all directions about a horizontal axis and oscillation about the axis of the valve stem; means for agitating the feed plate; and mechanism for moving the valve stem to regulate the displacement of the feed plate from the hopper mouth.

- 10 15 9. An acetylene generator including in combination, a carbide hopper having a feed opening; a vertically agitated feed plate for controlling the feeding of carbide from the hopper, said feed plate having a central conical portion for breaking up arching of the carbide in the feed opening and having a peripheral portion of less slope adapted to prevent free feeding of the carbide; a regulating lever operably connected with the feed plate, feed plate operating means for moving said lever to raise and lower the feed plate to control its displacement from the hopper opening, and other means operably connected with the lever for transmitting agitations through the lever to the feed plate, and a fulcrum for said lever spaced from its connections with the raising and lowering means and the agitating means.

- 20 25 30 35 10. An acetylene generator including a carbide hopper, a feed plate at the mouth of the hopper, said feed plate including a central coni-

cal portion extending into the hopper mouth, a lever operatively connected with the feed plate for regulating the displacement of said feed plate, a fulcrum for said lever, pressure-operated means connected with the lever at a substantial distance from said fulcrum for moving the lever to control the feed plate displacement, said feed plate including a peripheral portion of less slope than the central portion, the slope and extent of the peripheral portion being of such a nature 10 that said peripheral portion prevents free feeding of the carbide when the feed plate is in its position of maximum displacement, and other means operatively connected with the lever at a substantial distance from the fulcrum and 15 from the connection of the lever with the feed plate for agitating said lever to agitate the feed plate.

11. In an acetylene generator having a body, a carbide hopper, a valve movable toward and 20 from the hopper mouth to control the rate of feed of carbide from the hopper, pressure operated means fixed to the generator for controlling the extent of opening of the valve, said valve having a central conical portion that projects 25 into the hopper mouth, and a peripheral portion of less slope than the central portion, said peripheral portion having an extent and slope that prevents free feeding of the carbide when the valve is in its wide-open position, other 30 means for agitating the valve, a common lever connecting the controlling means and the agitating means with the feed valve, said lever extending transversely of the direction of movement of the valve toward and from the hopper 35 mouth, and a fulcrum for said lever fixed with respect to the body of the generator.

GEORGE M. DEMING.
